TOY REGISTER BANK

Jacob Farber, New York, N. Y.

Application September 24, 1954, Serial No. 458,189

1 Claim. (Cl. 235—100)

This invention relates to toy register banks, and an object thereof is the provision of a new and improved construction whereby, upon deposit of a coin, the recording indicia automatically record the new total contained in the bank, the structure containing two gears, one of which is moved through a tooth each time a coin is deposited, and the other of which is moved through a tooth by the first gear upon completion of each revolution of the latter.

Another object of the invention is the provision of a novel spring means of unitary construction engaging both of the above-mentioned gear to limit them to rotation through an arc of one tooth at a time.

Still another object of the invention is the provision of a toy register bank which is extremely simple in construction and operation and inexpensive in cost of manufacture.

The above as well as additional objects will be clarified in the following description wherein characters of reference refer to like-numbered parts in the accompanying drawing. It is to be noted that the drawing is intended solely for the purpose of illustration and that it is therefore neither intended nor desired to limit the invention necessarily to any or all of the exact details of construction shown except insofar as they may be deemed essential to the invention.

Referring briefly to the drawing, Fig. 1 is a perspective view of a toy register bank embodying the features of the present invention.

Fig. 2 is a sectional view taken on the line 2—2 of Fig. 4.

Fig. 3 is a sectional view taken on the line 3—3 of Fig. 2.

Fig. 4 is a sectional view taken on the line 4—4 of Fig. 2.

Fig. 5 is a rear elevational view of the bank, with parts broken away and partly in section.

Fig. 6 is a perspective view of the two gears of the device and the slide door for opening the bank to remove the coins, showing the gears in position to permit lifting of the door when the capacity of the bank has been deposited and showing the door in fully lifted position.

Referring in detail to the drawing, the housing of the bank comprises two preformed and fitted interlocked portions 10 and 11. The former is a single piece including the bottom or floor 12 and the two side walls 13 and 14; the latter is also a single piece, including the rear wall 15, the roof 16, and the sloping front wall 17 whose lower portion has a step formation 18 to simulate a cash register.

Pivoted in a common horizontal plane against the roof 16 are two wheels 19 and 20, each having ten spaced depending teeth 21 and 22, respectively. A slide 23 is slidably supported in rails 24 against the inner surface of the wall and has a handle 25 extending forward through the wall at right angles to the slide. A portion of the wall 17 in alignment with the slide, at the left, Fig. 1, is cut away at 26 to permit movement of the handle 25 a

2

given distance to the right. The other end of the slide, inside the housing, has a U-shaped coin-holding deformation 27 at right angles to the slide. A spring 28 secured at one end to the wall 17 and at the other to the slide, normally keeps the slide in the position shown in Figs. 1 and 3, stopped by the rails 24. A coin slot 29 through the wall 17 is aligned with the entrance 30 into the deformation 27, Fig. 2. A shelf 31 is secured against the wall 17 under the slot 29.

When a coin, such as a dime, for example, is inserted through the slot 29 it enters the coin-carriage 27 and rests on the shelf 31. Then, upon movement of the slide 23 by means of its handle 25 to the right, Fig. 1, upward, Fig. 3, the coin 32 will be moved off the shelf to drop to the floor. As seen in Fig. 3, however, during such movement of the coin it will engage a tooth 21 of the gear 19 and turn the gear through one-tenth a revolution. The number of dimes thus deposited will be visible through an opening or window 33 in the roof, in the usual manner, owing to the series of numbers 34 printed on the gear 19.

The gear 19 has a long tooth 35 extending outward toward the gear 20, so that once each turn of the gear 19 the tooth 35 will register between teeth 22 of the gear 20 and turn the latter through one-tenth of a revolution. The number of one-tooth turns through which the gear 20 has thus been turned will appear through the window 36 owing to the series of numbers 37 on the gear 20. A blind window 37 on the roof adjacent the window 33, is printed with a zero. Thus, the window 33 in cooperation with the window 37 will always read the sum of the dimes deposited in excess of or less than an even dollar amount, while the window 36 will read the dollar amount.

To limit each of the gears to rotation through a single tooth-length arc at a time, the following means is provided. A unitary length of resilient material in the form of a strip is deformed to provide a base 38 secured against the rear wall 15 between the gears 19 and 20; the strip has its extremities, or extensions, deformed to extend forward from the wall 15 and in a mutually converging direction, shown at 39 and 40. Each extension of the strip has a hump 41 formed near its end, adapted to engage in the space between two successive teeth of the gear. Thus both gears, when turned, are under constant frictional engagement with the extensions or springs 39 and 40, and as soon as either has completed a one-tooth turn the hump of the spring snaps into the next successive space and thus stops the gear from turning too far or being inadvertently returned to its original position.

A coin removal opening 42 is, as usual, provided in the back wall 15, and a vertically slidable door 43 normally closes this opening, because of the spring 44. Approximately the upper half of the door is cut away in its intermediate portion to provide two like upstanding arms 45 slidable through slots 46 in the roof parallel with the rear wall 15. The arms are provided with forwardly extending wings 47 at right angles to the door, terminating below the upper ends of the arms 45 and normally positioned, when the door is closed down, below the gears 19 and 20. The gear 20 has a slot 48 and the gear 19 a similar slot 49, however, through which the wings 47 may pass upward when these two slots are both aligned with the wings, which is the case when the sum of the coins deposited in the bank is equal to its capacity, say, for example, ten dollars. Then the door is free to be raised, provision, of course, being made in the roof by providing additional slots 50 communicating with the slots 46 in the roof, for the passage through the roof of the wings 47. A hand grip 51 is provided on the door so that it may be raised against the force of the spring 44.

Obviously, modifications in form or structure may be

provided without departing from the spirit or scope of the invention.

I claim:

A toy register bank comprising a housing simulating a cash register and including a rear wall, a bottom wall, side walls, a sloping front wall, and a roof, a wheel rotatably mounted against the roof and having depending spaced teeth, a horizontal slide slidably mounted against the front wall and having at one end thereof a forwardly extending handle, said front wall having a cut-out portion at one side thereof having said handle project therethrough, a coin receiving slot in said front wall, the other end of said slide having a U-shaped deformation comprising a coin carriage the entrance of which between the ends of the arms of the U faces the front wall and is normally positioned in alignment with said slot, resilient means normally urging said slide toward one side of the housing, limit stop means limiting movement of the slide toward said one side as aforesaid, a flat shelf secured under the base of said slot against the front wall and sloping downward into the housing at right angles to the front wall, said coin carriage being open at the top and

bottom between the arms of the U and having a height substantially smaller than the diameter of the coins to be used, the distance between said shelf and said wheel being approximately equal to the diameter of the coin whence when a coin in said carriage rests on said shelf and against the base of the U and the coin projects into a space between the teeth of said wheel, movement of the slide handle toward the middle of the front wall causing the carriage to carry the coin across the shelf and simultaneously causing the coin to turn said wheel through an arc of one tooth, said shelf having a width such that upon completion of said one-tooth turn the coin passes over the shelf and falls to the bottom of the housing, and resilient means engaging said wheel for limiting rotation thereof to an arc of one tooth at a time.
